UNITED STATES PATENT OFFICE.

PHILIP C. TRAVER, OF NEW YORK, N. Y., ASSIGNOR TO MICHAEL P. McNAMARA, OF NEW YORK, N. Y.

REPAIR DEVICE FOR PNEUMATIC TIRES.

No. 866,539.

Specification of Letters Patent.

Patented Sept. 17, 1907.

Application filed July 26, 1906. Serial No. 327,929.

To all whom it may concern:

Be it known that I, PHILIP C. TRAVER, a citizen of the United States, residing at Far Rockaway, city and State of New York, have invented certain new and useful Improvements in Repair Devices for Pneumatic Tires, of which the following is a specification.

This invention relates to repair devices for pneumatic tires and directly to that class of such devices as are peculiarly applicable to that class of pneumatic 10 tires known as double tube tires, comprising an inner "air tube" and an outer protecting case.

In the drawing accompanying this specification is illustrated one embodiment of my improvement and therein

15 Figure 1 is a perspective view of my improved tire repairer. Fig. 2 is a perspective view of a part of my device showing the protecting lining. Fig. 3 is a cross section of a double tube tire showing my improved device applied thereto. Fig. 4 shows an alternate arrangement 20 of one means for preventing the shifting of the device when in use. Fig. 5 shows a further adaptation of the arrangement of Fig. 4.

My device is intended for insertion between the outer and inner tubes of a double tube tire to protect the inner tube against possible rupture or injury by contact 25 with any hole or break in the outer tube or roughness caused by wear or otherwise in the inner portion thereof. Said device is also efficient to relieve strain caused by the inflated inner tube on worn or weakened portions 30 of the outer case.

The present improvement comprises a body portion, or plate 5 pre-shaped to approximate conformity to the contour of the tube to which it is to be applied, and having a flange 10 turned back on the inner edge thereof for 35 engagement with the heel as 14 of the outer tube or case. This flange serves to hold the device in place when in use. Said plate 5 preferably comprises more than a half-circle in cross-section, so that said repair device may be efficient to protect the inner tube against a 40 break or injury in the tread portion as well as in the side of the case. Said plate 5 preferably has those edges 50 thereof which are designed to contact with the inner face of the outer tube, bent more or less outwardly, whereby the said edges are prevented from injurious 45 contact with the inner tube and said outwardly turned edges bite more or less into the inner face of the outer tube thereby affording additional holding means to prevent displacement of the device. Plate 5 is preferably formed integral, that is of one continuous piece of sheet 50 metal or other suitable sheet material, such for instance as indurated fiber or woven fabric. Flange 10 either with or without the assistance of the outwardly turned edge 50 is usually sufficient to hold the device securely in place when in use but additional means as outwardly

projecting teeth 7 may be provided for engagement with 55 the inner face of the outer protecting case 9 to assist in maintaining the repair device against shifting or displacement. Said teeth while of sufficient length to properly grip the inner portion of the outer case are not of sufficient length to perforate said case. 60

If plate 5 is made of metal, teeth 7 are preferably formed integral therewith by punching and bending outward said teeth from the body of the plate. If plate 5 is composed of material unsuitable for the formation of teeth therefrom, said teeth may be made separately 65 of some suitable material and inserted in plate 5. One embodiment of such alternate construction is illustrated in Fig. 4 wherein 5 represents a section of the plate, said plate being perforated by a pin or tooth 11 having a head 12 against the inner side of plate 5 and a 70 retaining washer 13 fitting tightly about said tooth 11 on the outer side of plate 5.

In some cases it is advantageous to supply a lining 6 (Fig. 2) fitted to the inner face of my device. Said lining is preferably formed of some yieldable sheet 75 material and is so disposed on the face to which it is applied as to provide a lip 60 overhanging edge 50 of plate 5 around a portion of its periphery thereby forming a yieldable edge for said plate 5. Said lining serves to further protect the inner tube against abrasion by edge 80 50 of plate 5. Said lining 6 may be secured by any convenient means to the inner face of plate 5. In case plate 5 is provided with perforating teeth 11, said teeth may be also employed to retain lining 6 in place on plate 5, as shown in Fig. 5 wherein said pins pass 85 through plate 5 and lining 6 and by means of head 12 and washer 13 clamp said members 5 and 6 securely together.

My improved repair device is applied as follows. Inner tube 8, being deflated, one side as 14 of protecting 90 case 9 is withdrawn from wheel rim 15, and the repair device inserted between that portion of case 9 in which the break is located, and tube 8. Flange 10 is fitted to heel 14 of case 9 and said case replaced in rim 15. Inner tube 8 is then inflated whereby said tube is pressed 95 firmly against the repair device and said repair device forced firmly against the inner surface of case 9, flange 10 being thereby gripped between heel 14 of said case and the inner face of rim 15, edges 50 of said device sinking more or less into said inner surface of case 9 100 and aiding flange 10 to hold the repair device in place. If the device is supplied with teeth as 7, said teeth will be embedded securely in the inner face of case 9 thereby affording added means for preventing the shifting of the device. 105

If plate 5 is formed of metal or other relatively rigid material my repair device may be made in various sizes and shapes to conform to various contours of tires

respectively, and said device may also be made in various lengths.

I claim:

1. A protecting device for the inner tube of a pneumatic tire comprising a relatively rigid body member having a flange on that edge thereof contiguous to the heel of the tire casing for engagement with said heel and having the other edges of said body member curved outwardly for engagement with the inside of said tire casing and for protecting the inner tube against abrasion by said edges.
2. A protecting device for the inner tube of a pneumatic tire comprising a relatively rigid body member extending over and beyond the middle line of the inner tube to hold said tube under tension and having on one edge thereof a flange adapted to be gripped between the heel of the tire casing and the wheel rim.
3. A repair device for pneumatic tires comprising a relatively rigid body member extending over and beyond the middle line of the inner tube to hold said inner tube under tension, said body member having a yieldable edge and a rigid flange for engagement with the heel of the tire casing and the wheel rim.
4. A protecting device for the inner tube of a pneumatic tire comprising a relatively rigid integral body member having a flange on one edge thereof adapted to be gripped between the heel of the tire casing and the wheel rim, said body member being provided with teeth for engagement with the inner face of the tire casing.

Signed this 23rd day of July, 1906 in the presence of 30 two subscribing witnesses.

PHILIP C. TRAVER.
